UNITED STATES PATENT OFFICE.

DELOS A. DAVIS, OF AMES, IOWA.

SELF-MASKING FILM.

1,250,099.

Specification of Letters Patent. Patented Dec. 11, 1917.

Application filed May 25, 1916. Serial No. 99,848.

To all whom it may concern:

Be it known that I, DELOS A. DAVIS, a citizen of the United States of America, residing at Ames, in the county of Story and State of Iowa, have invented certain new and useful Improvements in Self-Masking Films, of which the following is a specification, reference being had therein to the accompanying drawing.

- 10 This invention relates to a self-masking film and has for its object the production of a film or plate or other sensitized negative wherein the film or plate is provided with a mask border around the edges thereof 15 of in order that a print may be taken therefrom, and a white border be formed around the edge of the print without the necessity of employing an additional or substitute mask.
- 20 Another object of this invention is the production of a simple and efficient means whereby the mask is formed directly upon the film or other negative, thereby allowing a clear cut border to be formed around the 25 edge of the picture.

Other objects and advantages of the present invention will appear throughout the following specification and claims.

- In the accompanying drawing:
- 30 Figure 1 is a plan view of a portion of a film after the same has been developed showing the mask formed thereon.

Fig. 2 is a plan view of the print taken from one of the pictures taken upon the film 35 shown in Fig. 1.

Fig. 3 is a plan view of a sensitized plate prior to the development thereof, showing the mask formed around the edge of the plate.

- 40 By referring to the drawing it will be seen that 1 designates the film which is made of the usual or desired structure, and this film is provided with a mask border 3 around each side edge thereof, which mask border 3 is connected at proper intervals to suit the different size or shape of the picture desired to be taken by means of a mask bar 4. This mask border and bar 4, of course, form a continuation around the 45 edge of the picture, the bar 4 being substantially twice as wide as the border 3 so as to allow sufficient space at each end of each

film to produce the desired border upon the end of the print which is to be printed. It should be understood that the mask may 55 be formed of any suitable or desired color, but it is preferable to form the mask of a ruby color in view of the fact that the light will have less effect upon the sensitized paper placed under the negative 60 through a ruby color surface than through any other color. However, as stated above, it is not desired to limit the invention to any particular color of border or mask formed around the film.

As illustrated in Fig. 2 it will be seen that a print 2 has been shown taken from the negative indicated by the numeral 5, wherein a border 6 is shown formed around the edge of the print, the border showing 70 upon the print white and the other shades being formed upon the face of the print as is usual with such prints taken from a negative.

In Fig. 3 there is shown a modification 75 of the invention wherein a sensitized plate 7 is employed having a border or mask 8 formed around all four edges thereof of suitable width to produce a desired border upon a print, this mask or border 8 being 80 formed preferably of a ruby color or any other desired color to suit the convenience of the person using or manufacturing the sensitized mediums, such as a plate or film.

Having thus described the invention what 85 is claimed as new, is:

As a new article of manufacture, a sensitized medium for use in photography, said medium having separated exposure fields and being provided with margins of actinically opaque material formed along its edges, said sensitized medium being further provided with a plurality of equally spaced transverse stripes of actinically opaque material extending between its exposure fields, said transverse stripes being of substantially twice the width of said margins, whereby a border of equal width may be formed around a print made from a detached negative, formed in any one of 95 100 said fields.

In testimony whereof I hereunto affix my signature.

DELOS A. DAVIS.
